UNITED STATES PATENT OFFICE.

LORRAINE VIVIAN CANTRELL, OF WICHITA, KANSAS.

FLUID-PRESSURE GAGE.

1,246,542.

Specification of Letters Patent. Patented Nov. 13, 1917.

Application filed April 18, 1916. Serial No. 91,959.

To all whom it may concern:

Be it known that I, LORRAINE V. CANTRELL, a citizen of the United States, and a resident of Wichita, in the county of Sedgwick and State of Kansas, have invented a new and Improved Fluid-Pressure Gage, of which the following is a full, clear, and exact description.

Among the principal objects which the present invention has in view are: to provide means for automatically determining the supply of fluid to accord with the pressure in the receptacle therefor; to provide means for pre-arranging the condition under which the apparatus operates; and to provide a simple and efficient mechanism for accomplishing the purposes above mentioned.

Figure 1 is a longitudinal sectional view of a gage constructed and arranged in accordance with the preferred embodiment of the present invention;

Fig. 2 is a top view of the same;

Fig. 3 is a cross section taken as on the line 3—3 in Fig. 1;

Fig. 4 is a longitudinal section of a gage constructed and arranged in accordance with a modified form of the present invention;

Fig. 5 is a top view of the gage shown in Fig. 4;

Fig. 6 is a cross section, said section being taken as on the line 6—6 in Fig. 4;

Fig. 7 is a detail view on an enlarged scale, showing, in longitudinal section, the piston head with which the plunger used in the gage is provided.

Description.

In the preferred form of the invention, as seen in Figs. 1 and 2, an elongated tube 9 is employed, having attached thereto a nozzle 10, the nib 15 of which is adapted for disposition over and upon a valve for the introduction of air to the inner tube of a pneumatic tire. The tube 9 is divided internally by a partition ring 16 fixedly held in said tube. The ring 16 forms a guide and support for an inner tube 18 slidably mounted therein. The tube 18 is supported at the rear end, by a collar 32, and centrally by the sliding block 26 with which it is rigidly connected. The block 26 is movable lengthwise in the tube 9, and is fixed in its adjusted position thereon by means of a screw 30. The screw 30 is threadedly engaged with the block 26 and freely passes through

a clamping plate 25 and a slot 27 furnished in the tube 9.

When the screw 30 is released the block 26 and the tube 18 mounted thereon is adjustable lengthwise of the tube 9, carrying with the block the nipple 33 provided to receive in holding relation an air supply pipe 35.

Within the tube 18 are slidably mounted a piston valve 19 and a closure plug 20, the said valve and plug being fixedly mounted on a hollow tube 37. The plug 20 closes the end of the tube 37 with which it is connected, to prevent the air admitted into the said tube by the elongated slots 38, escaping at the rear end thereof. The forward end of the tube 37 is open where the said tube passes through the piston 21 which has a sliding fit with the tube 9.

The piston 21, tube 37 and parts connected therewith are normally held in an advanced position by a spiral compression spring 23. The spring 23 is held between the piston 21 and the collar or partition ring 16. The spring 23 is compressed when the air pressure in the nozzle 10 and the pneumatic tire connected therewith exceeds the expansive force of said spring. As in similarly constructed springs, the expansive force increases as the spring is compressed, the degree of compression being ascertained in pounds. The calibrations or markings indicative of said pressure, are disposed at the side of the slot 27, as seen best in Fig. 2 of 90 the drawings.

To register with the calibrations referred to, pointers 39 are provided on the plate 25 in line with the center bore of the nipple 33. The bore of the nipple 33 is closed by the piston valve 19 when the same is moved across the path of the bore and in correspondence with the movement of the tube 37 and piston 21 connected therewith.

Thus it will be seen that in the operation of the gage, of the calibrations correspond in pound ratio with the resistance of the spring 23, the block 26 may be adjusted to move the nipple 33 until the pointers 39 thereon register with the calibrations at the side of the slot 27 in correspondence with the pressure regulating the delivery of the air through the nozzle 10. That is to say, if it is desired to deliver air until the pressure in the pneumatic tire registers eighty pounds, then the screw 30 is released and the block 26 and nipple 33 thereon is moved toward the rear

end of the tube 9 until the pointers 39 register with the calibration mark "80".

During the above described movement of the block 26 and parts connected therewith, 5 the spring 23 is maintained the previous position of the piston 21, valve 19 and parts connected therewith, or, in other words, the bore of the nipple 33 has been proportionally removed from the valve 19.

- 10 When, now, air is admitted to the tire through the nozzle 10, the pressure of the air being delivered on the face of the piston 21, will have to compress the spring 23 until the piston valve 19 is moved backward 15 to cover the bore of the nipple 33. This requires eighty pounds of pressure exerted upon the piston 21.

Modification.

20 In the modified form of the invention shown in Figs. 4 to 7 inclusive, to one end of the tube 9 is secured the nozzle 10, by means of a gland nut 11, said tube having a machine-faced flange 12, to hold the packing 25 13 inserted between the said flange 12 and the corresponding flange 14 on the gland nut. The packed delivery nib 15 is provided for fitting over the valve stem of the pneumatic tire tube for the filling of which the 30 gage is particularly designed. The tube is longitudinally divided by the partition ring 16, which is centrally bored and held in place by screws 17 or other suitable fastening devices.

35 The partition ring 16 forms a sliding support for the inner tube 18, which affords a sliding support for the valve 19 and plug 20. The valve 19, plug 20, and piston 21 are coaxial and rigidly mounted on a plunger rod 22.

40 Interposed between the ring 16 and the rear face of the piston 21, is the coiled compression spring 23, which normally moves the piston 21 to rest against the abutment 24 45 adjacent the connection of the tube 9 and nozzle 10. It will be understood that in service the spring 23 is normally under tension, to be initially moved by a known pressure. As shown in the accompanying drawings, this pressure would be thirty pounds, as indicated by the forward edge of the slide plate 25 registering with the calibration designated by the numeral "30". The plate 25 is supported on the sliding block 26, in 55 which the tube 18 is rigidly held to move therewith. The block 26 is guided lengthwise of the tube 9 by slots 27 formed therein. To this end, lateral extensions 28 and 29 are fitted to said slots, the former being rigidly 60 connected to the plate 25, which, as shown best in Fig. 5 of the drawings, overlaps the edges of the upper slot 27, and is used to clamp the block in set position whenever the screw 30 is tightened to clamp said plate 65 upon the tube 9.

The rear end of the tube 9 and the slots 27 formed therein is closed by a plug cap 31. To avoid any possibility of clamping of the block 26 in the tube 9, the tube 18 is furnished, adjacent the rear end, with the 70 fitted collar 32, as shown best in Fig. 4 of the drawings.

The extensions 28 and 29 form the base of nipples 33 and 34. The nipples 33 and 34 are extended to form connections for the 75 supply pipe 35 and connection pipe 36, respectively. The said nipples, extensions and block, and pipe contained therein, are bored to provide suitably reduced coaxial passages.

80

Operation.

If the nib 15 is provided with a check valve, the operator grasping the tube 9 as a handle, presses the nib over the inlet valve 85 of the tube of a pneumatic tire. The spring 23 operating normally to hold the piston 21 against the abutment 24 and the valve 19 removed from the passages in the nipples 33 and 34, air or other fluid is transmitted 90 from the supply pipe 35, through the tube 18 at the rear of the valve 19, through the tube 37 or pipe 36, to the nozzle 10, and thence to the pneumatic tube, on the valve of which the nib 15 is pressed.

95

When the pressure in the pneumatic tube and in the nozzle 10 is greater than the resistance of the spring 23, the same is compressed, the fluid in the nozzle 10 moving the piston 21, tube 37, or rod 22, and valve 100 19 backward until the said valve covers the ends of the passages in the nipple 33, or 33 and 34, thereby suspending the supply of air to the nozzle 10.

100

Prior to pressing the nozzle 10 upon the 105 tire valve, the operator adjusts the block 26 and the plate 25 thereon, upon the tube 9, and in accordance with the calibrations at the edge of the slot 27. Thus, if it be desired to supply the pneumatic tube with 110 air or fluid up to a pressure of eighty pounds, the screw 30 is manipulated to release the plate 25 from its grip on the tube 9, and the block 26 is moved toward the rear end of the tube 9 until the registering 115 edge of the plate 25 or pointers 39 corresponds with the calibration indicated by the numeral "80". This would indicate that a pressure of eighty pounds upon the piston 21 would be required to move the same 120 against the resistance of the spring 23, to interpose the valve 19 in the path of the passages in the nipples 33 and 34. When the eighty pounds of pressure is attained, the operation of the valve 19 is the same 125 as above described.

120

It will be understood that the block may be shifted to predetermine any pressure from the minimum to the maximum for which the apparatus is intended, and that 130

automatically when the pressure introduced in the tube arrives at that indicated by the plate 25 and the calibrations on the tube 9, the supply of air or fluid will be determined.

5

Claim.

A fluid pressure gage comprising a delivery nozzle; a tube supporting said nozzle and having a hollow nipple extending laterally therefrom; a valve reciprocatively mounted in said tube adapted to close the entrance of said nipple thereto; a piston reciprocatively mounted in said tube adjacent said nozzle, the face of said piston being exposed to the pressure in said nozzle and relatively larger than the area of said valve; means rigidly connecting said piston and said valve; a connection pipe operatively uniting said nozzle and the end of

said tube opposite that with which said nozzle is engaged, one end of said pipe being disposed in the path of said valve to be closed thereby; a spring for normally maintaining said valve between said nipple and said nozzle, said spring being adapted to yield under pressure applied upon said piston to move said valve in closed relation to the opening of said pipe to said tube; and means for moving said nipple relatively to the normal position of said valve for varying the extent of movement of said valve preliminary to closing the entrance to said nipple.
